(57) **CLAIM**

The ornamental design for a bottle with ten panel oval shoulder, as shown and described.

DESCRIPTION

FIG. 1 is a top, front perspective view of a bottle with eight panel oval shoulder, showing my design;

FIG. 2 is a front elevational view thereof, the rear, left side, and right side elevational views being identical;

FIG. 3 is a top plan view thereof; and,

FIG. 4 is a bottom plan view thereof.

The broken lines shown in the drawings of a portion of the bottom surface are included for the purpose of illustrating environmental structure that forms no part of the claimed design.
